FUEL SUPPLYING APPARATUS

Charles M. Bovard, Mount Vernon, Ohio, assignor to Cooper-Bessemer Corporation, Mount Vernon, Ohio, a corporation of Ohio

Application June 30, 1937, Serial No. 151,118

7 Claims. (Cl. 123—140)

The invention relates to apparatus for supplying liquid fuel to internal combustion engines, of the type in which a predetermined liquid pressure is maintained in a header from which the fuel is distributed and injected into the cylinders by suitable mechanically operated and timed needle valves. In fuel supplying systems of the above character it has been customary to provide a pressure regulating valve on the delivery side of the pump, which operated to relieve the pressure when in excess of the pressure for which the valve was set, and also relieved the excess fuel supplied by the pump beyond the needs of the engine. Systems of the above character have given rise to serious operating troubles involving erosion and wear of the valves and their seats, due to the fact that the fuel injection pressure usually runs up into thousands of pounds, and the fuel at this exceedingly high pressure, along with the frequent opening and closing of the valves, acts almost as badly as a solid material in respect to wear and erosion. Numerous efforts have been made over a period of many years to provide a fuel feeding apparatus which would accurately maintain the desired pressure and avoid the excessive wear above referred to, but in so far as I am aware prior efforts of the above character have not performed satisfactorily in actual practice.

30. The present invention aims to provide a fuel supply apparatus which will avoid excessive wear as above referred to and other attendant objections in fuel supply systems of the character under discussion, and which will otherwise satisfy the special operating conditions and requirements met with in supplying fuel to engines of the Diesel type as contrasted to the general art of pumping liquids. For example and particularly in connection with modern higher speed engines, it is necessary to maintain an exceedingly high delivery pressure on the fuel—usually between 5,000 and 7,000 lbs. per sq. in.; and to secure uniform distribution of the fuel, this pressure must be very closely regulated to avoid fluctuations which would result in irregular performance of the engine, and yet it is also important that the rate of fuel supply be quickly and accurately adjustable to conform to changes in load conditions, which may involve altering the delivery pressure of the fuel (as in the preferred embodiment of the invention hereinafter described) as well as the amount of fuel pumped. The present invention also markedly reduces the power needed to operate the pump as compared to Diesel engine fuel pumps which supplied excess quantities of

fuel by-passed through a heat pressure relief valve as above described, and cuts down the heating of the fuel which was entailed in by-passing it.

In accordance with the present invention the intake of the fuel feeding pump is adjustably throttled in accordance with the pressure existing on the delivery side of the pump, and accordingly the pump plunger may draw in varying amounts of fuel (and produce a partial vacuum) on its suction stroke, thereby supplying only approximately as much fuel as is needed to maintain the pressure on the delivery side of the pump at the desired amount. With the above mode of operation the regulation of the fuel takes place on the suction side of the pump where high pressures as above referred to are not encountered, and accordingly rapid wear of the regulating parts is avoided; and it becomes unnecessary to provide a valve on the delivery side of the pump from which fuel must escape in regulating the pressure. Preferably, in a more specific aspect of the invention, the throttling effect upon the pump intake is regulated both according to the fuel pressure on the delivery side of the pump, and the load on the engine, so that the amount of fuel supplied by the pump conforms more closely to both of the above mentioned conditions of operation.

The primary object of the invention accordingly is to provide a fuel supplying apparatus of the above character which will operate reliably to maintain the desired pressure on the delivery side of the fuel pump, and afford long continued service without undue wear and erosion.

Further objects and advantages will be in part obvious and in part specifically referred to in the description hereinafter contained which, taken in conjunction with the accompanying drawings, discloses a preferred embodiment of the apparatus adapted to operate in accordance with the invention; the illustrated form of the invention however should be regarded as merely illustrative of the principles of the invention, in its broader aspects. In the drawings—

Fig. 1 is a vertical section of a fuel supplying apparatus constructed to operate in accordance with the invention, the section being taken on the lines 1—1 of Figs. 2 and 3, looking in the direction of the arrows.

Fig. 2 is a side elevation of the apparatus with certain parts cut away.

Fig. 3 is a transverse section taken on the line 3—3 of Fig. 2, and looking in the direction of the arrows.

Fig. 4 is a detail view showing more particularly

55

the throttling valve construction used in conjunction with the pump intake.

Fig. 5 is a schematic view showing diagrammatically the general mode of operation of the apparatus.

The invention is illustrated as applied to a fuel pump of the duplex type, involving duplicate pump units, a description of one of which will serve for both. Each pump may be regarded as 10 having a reciprocating pump plunger 1 (Figs. 1 and 3) driven by suitable mechanism which will not be described or illustrated in detail since mechanisms suitable for the purpose are known in the art. The pump member or plunger 1 15 operates in a pump chamber 2 which is provided with intake openings or ports 3, and a delivery opening 4 (Fig. 1) which latter is closed except during the delivery stroke of the plunger, by valve 5 urged against its seat by a spring 6. During 20 the delivery stroke of the plunger 1 the valve 5 opens and delivers fuel under high pressure (usually thousands of pounds per square inch) into a delivery passageway 7 (Figs. 1 and 2). From the passageway 7 the fuel under pressure is 25 distributed and injected into the engine cylinders by suitable mechanisms which need not be here described.

The path of the fuel to the pump chamber 2 appears best in Fig. 3, where a fuel inlet passageway 8 is shown as conducting the fuel through suitable ducts 9 (and a throttling valve construction hereinafter to be described) to a passageway 10 which latter by means of an annular chamber 11 is placed in communication with the intake ports 3 of the pump. Accordingly the pump plunger 1 during its suction stroke draws in liquid fuel from the passageway 8 through intervening connections, and during its delivery stroke the plunger delivers the fuel under high 40 pressure into the delivery passageway 7.

In accordance with the present invention I employ in conjunction with the intake openings of the pump, an adjustable fuel throttling valve, the position and throttling effect of which is regulated according to the liquid pressure then existing in the passageway 1; and whenever the liquid pressure in the passageway 1 rises beyond a predetermined value, the throttling valve is automatically shifted to increase its fuel throttling 45 effect and cause the pump to deliver a reduced amount of fuel to passageway 1. In other words to an extent depending upon the position of the throttling valve, the pump plunger 1 draws a variable amount of fuel into pump chamber 2, which 50 amount will be less than a full charge, and will result in the creation of a partial vacuum in chamber 2. Thus the amount of fuel pumped into the delivery passageway 7 and the liquid pressure in such passageway may be regulated 55 without resort to pressure regulating relief valves subject to the exceedingly high pressures which exist on the delivery side of the pump. A throttling valve on the pump intake as above described, is not subject to any substantial pressures nor to 60 the attendant erosion above referred to. Consequently the valve will afford long continued use without undue wear, leakage or unreliability in its action, and moreover adjustment or movement of the valve is much more facile since it does not 65 have to operate against high pressures. It has been found furthermore that an accurate and reliable control of the liquid pressure on the delivery side of the pump may be obtained in the above manner, which is highly important from the standpoint of practical operation.

The invention in its broader aspects does not depend upon the use of any particular type of throttling valve, but as shown in Fig. 3 this valve may be made in the form of a rotatable member 12 having an interior fuel receiving chamber 13 which is in communication with the ducts 9 above mentioned and this valve member 12 is provided with throttling ports 14, which afford communication between the chamber 13 and the passageways 10 which are respectively associated with the two pump units. Referring to Fig. 3 for example, the more the valve member 12 is moved angularly to shift the port 14 toward the right, the greater will be the throttling effect of this port upon the fuel flowing through the inlet ports 3 which are at the left of the figure, and the greater will be the partial vacuum drawn by the left hand pump plunger 1 during its suction stroke, and the smaller will be the amount of fuel delivered by the pump during each pressure 20 stroke. (In the form of the invention shown in Fig. 3 a valve sleeve 14a is shown as interposed between the valve member 12 and the passageways 10, but this valve sleeve may be ignored for present purposes.) In like manner as indicated 25 in Fig. 4, the remaining throttling port 14 of valve member 12 serves the pumping unit which is shown at the right of Fig. 3.

In order to adjust the position of the valve member 12 and its throttling ports 14 to maintain 30 the desired liquid pressure in delivery passageway 7, a regulating member is provided for the valve which shifts its position in response to pressure changes in passageway 1. In the illustrated embodiment of the invention this regulating member 15, as shown more in detail in Fig. 1, takes the form of a slide which is pressed by a spring 16 (adjustable as to pressure by stud 17) against a seat 18. Alined slideable plungers 19 and 20 bear against the slide 15, and plunger 20 40 is exposed to the pressure existing within passageway 7 by reason of the communicating ducts 21 and 22, which may have a fuel strainer 23 interposed between them. By adjustment of the stud 17 the spring 16 will be set at the pressure 45 which it is desired to maintain within the passageway 7, and whenever an excess pressure exists the plungers 20 and 19 will lift the slide 15 against the pressure of spring 16. Proportionate movement is imparted to the rotatable valve member 12 by suitable means, such as the rack teeth 24 (Fig. 3) on the slide 15 which mesh with gear teeth 25 on the adjacent end of valve member 12. Thus the valve member 12 and its throttling ports 14 are adjusted to provide an increased 55 throttling effect on the flow of fuel to the respective pumping units, whenever the pressure on the delivery side of the pump exceeds a predetermined amount.

Fuel regulation of the character above described may be combined with regulation in accordance with the fuel demand of the engine, by providing a second fuel throttling valve of the character above described, in the path of fuel flow to the pump. In the illustrated embodiment 60 of the invention the valve sleeve 14a, surrounding the valve member 12, serves this last mentioned purpose. As shown most plainly in Fig. 4 this valve sleeve 14a is provided with throttling ports 14b (similar in character to the ports 14 above described) which are interposed between the ports 14 and the passageway 10. Depending upon the angular position of the valve sleeve 14a, these last mentioned ports 14b impose a greater or less throttling effect upon the fuel passing into the 75

pumping units. The position of the valve sleeve 14a may be adjusted by an oscillating arm 27, which latter may be connected to some part on the engine which is adjusted in accordance with the fuel demand, such as the main throttle of the engine or the governor. As shown in Fig. 5, for example, the oscillating arm 27 may be connected by a link 28a to a collar 29a which surrounds the sleeve 30a of a suitable governor mechanism indicated diagrammatically at 31a, and carried by a spindle 32a which rotates at a speed proportional to engine speed. Numeral 33 in Fig. 5 indicates diagrammatically a hand throttle which may also be used to control the engine, but the diagrammatic showing of the figure should be regarded merely as suggestive of mechanisms well known in the art for governing the engine.

Fig. 5 also indicates diagrammatically by rectangles, the throttling valves 12 and 14a as interposed in the full inlet to the pump chamber, and indicates by the double headed arrows that the position of the throttling valve 12 is adjusted according to the pressure in the fuel delivery passageway, and that the position of the throttling valve 14a is adjusted according to the position of some part on the engine, such as the governor 31a or main throttle 33, which is adjusted in position according to the fuel demand of the engine. When both throttling valves are employed, the valve 14a accordingly modifies the throttling effect of valve 12 in accordance with the fuel demand, thereby facilitating the maintenance of the desired liquid pressure in delivery passageway 7, under different operating conditions. Controls of the above character may be very readily and quickly adjusted to satisfy different operating conditions.

In the construction of apparatus as above described it is very advantageous to reduce to a minimum the volume of the passages between the throttling valve and the pump plunger since unduly wide fluctuations of fluid pressure in the delivery passageway 7 otherwise are likely to occur. However the apparatus may be readily built in the form of a compact and self-contained unit which will avoid the above difficulty.

In order to protect the apparatus against excessive pressures in the delivery passageway 7, in the event that the normal regulating members above described should fail to function for any reason, I may also provide a pressure relief valve 28 (Fig. 2) which is in communication with the delivery passageway 7 through a duct 29. The spring 30 which holds valve 28 closed, will normally be set to release the valve only in the event that the pressure in passageway 7 builds up substantially beyond the normal range. Should this happen, valve 28 opens and the excess fuel passes through openings 31 into the drain cup 32. Thus the valve 28 serves only as an emergency relief and does not enter into the normal operation of the apparatus. On the contrary a valuable feature of the apparatus is, as previously explained, that it needs no pressure regulating valve on the high pressure side of the pump, in normal operation.

In accordance with the present invention only so much or so little fuel need be pumped as is required to supply the then existing demand of the engine, and the fuel so supplied is maintained at the desired pressure. In other words, all of the fuel pumped goes to the engine, in contrast to prior systems involving pressure regulating valves as above mentioned, in the operation of which more fuel than needed was pumped, and

the excess relieved from the high pressure delivery line.

While the invention has been described as carried out by an apparatus of specific construction, it should be understood that many changes may be made therein without departing from the principles of the invention in its broader aspects, within the scope of the appended claims.

I claim:

1. Apparatus for supplying liquid fuel under predetermined pressure to internal combustion engines, having a pump chamber provided with intake and delivery openings, a pump member operating in said chamber, an adjustable fuel throttling valve in communication with said intake opening which throttling valve is constructed and arranged to cause the pump member during suction strokes to draw in varying amounts of fuel into the pump chamber and produce a varying partial vacuum in said chamber according to the adjustment of said throttling valve, and means responsive to fuel pressure changes on the delivery side of the pump for adjusting the position of said throttling valve to regulate the amount of fuel pumped in accordance with the fuel pressure on the delivery side of the pump.

2. Apparatus for supplying liquid fuel under predetermined pressure to internal combustion engines, having a pump chamber provided with intake and delivery openings, a pump member operating in said chamber, fuel throttling valve members located in the path of fuel flowing to said pump chamber, said throttling valve members being constructed and arranged to cause the pump member during suction strokes to draw in varying amounts of fuel into the pump chamber and produce a varying partial vacuum in said chamber according to the adjustment of said throttling valve members, and means responsive respectively to fuel pressure changes on the delivery side of the pump and to the fuel demand of the engine, for adjusting the respective positions of said throttling valve members to regulate the amount of fuel pumped in accordance with the fuel pressure on the delivery side of the pump and the fuel demand of the engine.

3. Apparatus for supplying liquid fuel under predetermined pressure to internal combustion engines, having a pump chamber provided with intake and delivery openings, a pump member operating in said chamber, fuel throttling valve members in series with each other and said intake opening, said throttling valve members being constructed and arranged to cause the pump member during suction strokes to draw in varying amounts of fuel into the pump chamber and produce a varying partial vacuum in said chamber according to the adjustment of said throttling valve members, and means responsive respectively to fuel pressure changes on the delivery side of the pump and to the fuel demand of the engine, for adjusting the respective positions of said throttling valve members to regulate the amount of fuel pumped in accordance with the fuel pressure on the delivery side of the pump and the fuel demand of the engine.

4. Apparatus for supplying liquid fuel under predetermined pressure to internal combustion engines, having a pump chamber provided with intake and delivery openings, a pump plunger reciprocating in said chamber, a rotatable valve member having a fuel throttling port therein which is in communication with said intake opening which throttling valve is constructed and arranged to cause the pump member during suc-

tion strokes to draw in varying amounts of fuel into the pump chamber and produce a varying partial vacuum in said chamber according to the adjustment of said throttling valve, said apparatus having a fuel delivery passageway leading from said delivery opening and a regulating member for said valve which is movable in position according to the liquid pressure existing in said delivery passageway, means being provided to adjust the angular position of said valve member in response to changes in position of said regulating member to regulate the amount of fuel pumped in accordance with the fuel pressure on the delivery side of the pump.

5. Apparatus for supplying liquid fuel under predetermined pressure to internal combustion engines, having a pump chamber provided with intake and delivery openings, a pump plunger reciprocating in said chamber, a rotatable valve member having a fuel throttling port therein which is in communication with said intake opening, said apparatus having a fuel delivery passageway leading from said delivery opening and a regulating member for said valve member which is movable in position according to the liquid pressure existing in said delivery passageway, means being provided to adjust the angular position of said valve member in response to changes in position of said regulating member, 20 a rotatable valve sleeve enclosing said first mentioned valve member and also provided with a fuel throttling port interposed between the first mentioned port and the intake opening, said valve member and valve sleeve being constructed and arranged to cause the pump member during suction strokes to draw in varying amounts of fuel into the pump chamber and produce a varying partial vacuum in said chamber according to the adjustment of said throttling valve member, and 25 means whereby the angular position of said valve sleeve may be adjusted in response to changes in the fuel demand of the engine.

6. Apparatus for supplying liquid fuel under predetermined pressure to internal combustion engines having a pump chamber provided with intake and delivery openings, a pump member

working in said chamber, a throttling valve member positioned to control the flow of fuel to said intake opening which throttling valve member is constructed and arranged to cause the pump member during suction strokes to draw in varying amounts of fuel into the pump chamber and produce a varying partial vacuum in said chamber according to the adjustment of said throttling valve member, said apparatus having a fuel delivery passageway leading from said delivery 10 opening and a regulating member for said valve member which is movable in position according to the liquid pressure existing in said delivery passageway, means being provided to adjust the position of said valve member in response to 15 changes in position of said regulating member to regulate the amount of fuel pumped in accordance with the fuel pressure on the delivery side of the pump.

7. Apparatus for supplying liquid fuel under predetermined pressure to internal combustion engines having a pump chamber provided with intake and delivery openings, a pump member working in said chamber, a throttling valve member positioned to control the flow of fuel to said 20 intake opening, said apparatus having a fuel delivery passageway leading from said delivery opening and a regulating member for said valve member which is movable in position according to the liquid pressure existing in said delivery 25 passageway, means being provided to adjust the position of said valve member in response to changes in position of said regulating member, a second throttling valve member also positioned to control the flow of fuel to said intake opening, 30 said throttling valve members being constructed and arranged to cause the pump member during suction strokes to draw in varying amounts of fuel into the pump chamber and produce a varying 35 partial vacuum in said chamber according to the adjustment of said throttling valve members, and means whereby the position of said second mentioned throttling valve member may be adjusted in response to changes in the fuel demand 40 of the engine.

CHARLES M. BOVARD.
